CLAIM

The ornamental design for a docking station as shown and described.

DESCRIPTION

FIG. 1 is a top, front and right side perspective view of a docking station embodying our new design;

FIG. 2 is a bottom, rear and right side perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dot-dash broken line immediately adjacent shaded surfaces represents the boundary of the claim, which extend to the boundary but does not include the boundary; all other broken line depict portions of the docking station that form no part of the claim.
